UNITED STATES PATENT OFFICE.

JOHN SCHERNER, OF MILWAUKEE, WISCONSIN.

CLEANER.

Application filed April 29, 1921. Serial No. 465,361.

To all whom it may concern:

Be it known that I, JOHN SCHERNER, a citizen of the United States, and a resident of Milwaukee, in the county of Milwaukee, and State of Wisconsin, have invented certain new and useful Improvements in Cleaners, of which the following is a specification.

My invention relates to cleaners and the principal object of my invention is to provide a new and improved cleaner particularly adapted to clean electric lamps and electric lamp shades. In the drawings accompanying this specification and forming a part thereof I have shown, for purposes of illustration, one form of which my invention may assume. In these drawings the single figure represents an elevation of this illustrative form of cleaner having portions thereof shown in section.

The cleaner herein shown comprises a frame 11 which may be tubular as shown. Surrounding this frame is a collar 12 to which are secured by means of brackets 13 and pivots 14 a plurality of arms 15 preferably three in number. Each of these arms 15 is provided at its outer end with a hook 16 adapted to engage the rim of the lamp shade 17 to thereby clamp the cleaner to the lamp shade. Each arm 15 is operated by a rod 18 and the rods 18 are secured to and movable with a collar 19 surrounding the tubular frame 11 and adapted to be clamped in position on the frame by means of a tightening screw 20 passing through a pair of lugs 21 on the collar 19.

Passing through the tubular frame 11 is a shaft 22 provided at its lower end with a crank 23 and handle 24 and at its upper end with a crank 25 to which is pivotedly secured at 26 an arm 27 carrying a mass of dusting material 28 such as excelsior or waste which may be reinforced and held in position by means of a hand 29 secured to the arm 27. The arm 27 is in the form of a bell crank the second arm 30 of which is provided with a pin 31 adapted to ride in a groove 32 of a collar 33 slidably mounted upon the tubular frame 11 and movable vertically on said frame by means of a rod 34 extending to the lower part of the frame and provided with a finger piece 35 and guided by a bracket 36. The cleaner is also provided with an arm 37 which is provided with a hook 38 adapted to encircle the tubular frame 11 and with a hook 39 adapted to

encircle the neck 40 of the shade 17 and is also provided with a brush 41 formed of any suitable material and adapted to engage the top of the shade 17. The hook 38 may be provided with a suitable finger piece 42.

In operation the arms 15 are positioned adjacent the rim of the shade 17 and the collar 19 is then drawn down until the arms 15 firmly engage the shade 17 whereupon this collar 19 is clamped in position by means of the thumb screw 20. The arm 37 is then hooked over the neck 40 of the lamp shade 17. The crank 23 is then turned to rotate the shaft 22 and with it the arm 27 and the cleaning material 28 and as the cleaning material is rotated the rod 34 is raised by means of the finger piece 35 to gradually swing the cleaning material 28 toward the outer rim of the shade 17 to thereby clean not only the lamp but also the entire inside surface of the shade. The arm 37 is then rotated to clean off the top of the shade 17.

It will be obvious from the above that I have provided a new and improved device for cleaning lamps and lamp shades. The disclosure herein, however, is illustrative only and my invention is not limited thereto except as defined by the claims appended hereto.

I claim:

1. A cleaner comprising a body, a series of fingers mounted thereon and adapted to be moved to clamp to a lamp shade, means mounted on said body for so moving said fingers, and means also mounted on said body and adapted to clean at least a part of the lamp and lamp shade.

2. A cleaner comprising a body, a series of fingers mounted thereon and adapted to be moved to be clamped to a lamp and lamp shade, means mounted on said body for so moving said fingers, and means separate from said fingers and also mounted on said body adapted to clean at least a part of the lamp and lamp shade.

3. A cleaner comprising a body, means for clamping said body to a lamp and lamp shade assembly, and means mounted on said body for cleaning said lamp and the interior of said lamp shade.

4. A cleaner comprising a body, means for clamping said body to a lamp and lamp shade assembly, and means mounted on said body for cleaning said lamp and the interior and exterior of said lamp shade.

5. A cleaner comprising a body, means for clamping said body to a lamp and lamp shade assembly, and means mounted on said body for cleaning the interior and exterior of said shade.
6. A cleaner comprising cleaning means for cleaning a lamp globe and the inside of a lamp shade, means for shifting said cleaning means so that said cleaning means will be in position to clean various portions of said lamp globe and lamp shade, and means to operate said cleaning means in any such position.
7. A cleaner comprising means for detachably clamping the cleaner to a lamp shade and means, operative while said cleaner is so clamped to said shade, to clean a lamp positioned within said shade.

In testimony whereof I have signed my name to the above specification.

JOHN SCHERNER.
